ABSTRACT

A firearm, particularly a sports or target pistol, comprising an angle-lever breechblock mechanism, wherein an actuating or cocking lever is laterally mounted on the pistol for actuating the angle-lever breechblock mechanism.

FIG.5

**FIREARMS, ESPECIALLY SPORTS OR TARGET
PISTOL**

BACKGROUND OF THE INVENTION

The present invention broadly relates to firearms and, more specifically, concerns a sports or target pistol, especially a pistol which in its conception and design differs from the state-of-the-art sports pistols in that the breechblock mechanism and trigger mechanism are much simpler and inexpensive to manufacture, while nonetheless affording maximum firing accuracy.

The previously known types of sports or targets pistons, predominantly equipped with drop-block breech mechanisms or angle block-breech mechanism and a tensioning or cocking lever leading through the handle or stock, or those type of constructions employing a vertical sliding-and rotary breechblock mechanism coupled with the trigger guard serving as the cocking element, generally possess a trigger- or double-hair trigger system which is independent of the striker or hammer element and breechblock mechanism, and which system can be externally actuated by means of a lever. Such type pistols, wherein the firing- and breechblock mechanisms function independently of the trigger system, always require two types of movement on the part of the shooter, namely one movement for the purpose of lowering or rotating the breech-block cylinder or the breech lock coupled with the cocking or tensioning of the firing- and breechblock mechanism, and a second movement for setting the trigger system. All of these constructions are very complicated, requiring extreme accuracy in manufacture which, in turn, has a considerable influence upon the final cost of the pistol.

SUMMARY OF THE INVENTION

Therefore, there is a real need in the firearms art for a pistol of the mentioned type which is not associated with the aforementioned drawbacks of the prior art constructions. Accordingly, a primary objective of the present invention is to provide such a pistol which capably and effectively fulfills the existing need.

Another, more specific objective of the present invention is to provide an improved construction of pistol which only requires a single movement for cocking the firing mechanism, for initiating the operation of the breechblock mechanism, and for setting the trigger system, and additionally, simplifies the construction of the otherwise complicated and expensive breechblock- and trigger mechanisms.

Yet a further significant objective of the present invention relates to an improved construction of sporting or target pistol which is extremely simple to use, requiring a minimum of manipulations, economical to manufacture, provides for maximum firing accuracy, and is not readily subject to malfunction.

Now, in order to implement these and still further objects of the invention, which will become more readily apparent as the description proceeds, the inventive pistol is manifested by the features that the breechblock is constructed as an angle-lever breechblock mechanism which can be actuated by means of a cocking or tensioning lever mounted laterally of the breechblock mechanism.

BRIEF DESCRIPTION OF THE DRAWINGS

The invention will be better understood and objects other than those set forth above, will become apparent when consideration is given to the following detailed description thereof. Such description makes reference to the annexed drawings wherein:

FIG. 1 is a fragmentary longitudinal sectional view of the inventive angle-lever breechblock mechanism in closed condition as provided for a pistol;

FIG. 2 is a longitudinal sectional view of the angle-lever breechblock mechanism of FIG. 1, but this time depicted in its open position;

FIG. 3 to 5 depict respective fragmentary sectional views of the different components of the inventive pistol, and specifically wherein:

FIG. 3 illustrates details of the trigger mechanism in the unset condition;

FIG. 4 shows the cocking operation between the breechblock mechanism and the trigger mechanism; and

FIG. 5 illustrates the breechblock mechanism in the closed condition and the trigger mechanism in the set condition.

**DETAILED DESCRIPTION OF THE PREFERRED
EMBODIMENT**

Describing now the drawings, the exemplary embodiment of inventive sports or target pistol depicted in FIG. 1 illustrates the angle-lever breechblock mechanism in its closed position, embodying the breech block or breechblock cylinder 3 and the breech lock 7, supported by the support bolt or pin 8 vertically mounted in the breechblock housing 2. The breechblock cylinder 3 is coupled by a connection lever 5 and the pivot bolts or pins 6 and 4 with the breechblock or breech lock 7. By means of the cocking or tensioning lever 14 threadably connected laterally of or to one side of the breech lock 7, it is possible to laterally open and close at the left the angle-lever breechblock mechanism.

FIG. 2 illustrates this angle-lever breechblock mechanism in its open position. Under those circumstances the cocking or tensioning lever 14 is oriented substantially perpendicular to the breechblock cylinder 3, the extent of pivoting of this cocking lever 14 into the illustrated open position being limited by the lateral impact of the breechblock lock 7 at the breechblock housing 2 at location 2a thereof.

Owing to the angular movement of the breechblock lock 7, the pivot bolt 6, located at a predetermined distance from the supporting bolt 8, describes a circular arc. Due to the attendant action of the connection or connecting lever 5, mounted at the pivot bolt 6 of the breechblock lock 7 and at the pivot bolt 4 of the breechblock cylinder 3, the just mentioned breechblock cylinder 3 is retracted back within the bore 2b of the breechblock housing 2. During this movement the firing pin 9, subjected to the action of the firing pin spring 10, is located in its forward "fired" position. By virtue of this rearward movement the breechblock cylinder 3 frees the breech or changing chamber 38 of the breechblock housing 2. As a result, the angle-lever breechblock mechanism is thus disposed in its uncocked open condition or state.

Now the closing movement for the breechblock mechanism is undertaken in the reverse sense. Prior to the time that the cooperating surfaces 3a and 7a of the breechblock cylinder 3 and the breechblock lock 7 interengage or contact one another, and the radii of which are matched or accommodated to one another, the firing pin 9 is retained by the trigger seal 11 and the firing pin spring 10 is tensioned or loaded. The clocking or tensioning lever 14 must now overcome this tensioning force of the firing pin spring 10. When the tensioning or cocking lever 14 has nested against the breechblock housing 2, then, the arresting ball member 13 housed in the breechblock cylinder 3 and subjected to the pressure of the arresting spring 12, engages with the groove 7b of the breechblock lock 7, the angle-lever breechblock mechanism being secured in its closed position. The linear locking of the breechblock cylinder 3 and the breechblock lock 7 between the barrel portion 1 and the support pin 8 provides such a strong breech locking action that there is afforded exceptional precision.

Continuing, it is here remarked that the construction of the inventive pistol will be now best explained in conjunction with FIGS. 3 to 5 inclusive, and wherein initially reference is made to the illustration of FIG. 5. In that figure there is depicted the breechblock mechanism in its closed condition and the trigger mechanism in its set condition. The trigger sear 11 with its catch or lock nose 29, and pivotally mounted upon a bolt member 30 in the handle or stock 15, fixedly retains in position the cocked or loaded firing pin member 9 owing to the action of the upwardly effective spring member 16 bearing against the underside of the trigger sear 11 as shown. The disconnector 27, subjected to the action of the spring member 28, is mounted upon a bolt or pin 37 secured in the handle or stock portion 15. This disconnector 27 bears with its downwardly depending nose portion 33 upon the trigger arm nose 34. The configuration of the disconnector 27 is selected such that the mass thereof located beneath the point of rotation, namely below the pivot bolt 37, is so large that on the one hand the spring member 28 need not be too strong and the moved mass can equally release the trigger seal 11. On the other hand, the pressure of the nose portion or detent 34 of the disconnector 27 against the trigger arm nose 34 should not be too great, otherwise for an adjusted pressure point the trigger rod 26 no longer possesses the requisite play or required movement capability.

The trigger arm or rod member 26 contains all of the adjustment possibilities for the double-hair trigger screw 24 for the double-hair trigger, the pressure-point screw 20 for the pressure point, the screw member 18 for adjusting the interengagement of the nose members of the trigger arm or rod 26 and the disconnector 27, as well as the screw member 19 serving to secure the screw 18 and the adjustable trigger tongue or trigger member 17.

FIG. 3 illustrates details of the trigger mechanism in its unset squeezed-off or rest position. The firing pin member 9 is no longer loaded and the breechblock cylinder 3 is closed. The trigger sear 11 is disposed beneath the nose member or projection 35 of the firing pin 9 and the disconnector 27 is likewise released or unloaded. In such condition, this disconnector 27 is no

longer retained by the nose member 34 of the trigger rod or arm 26, so that the spring 28 moves the disconnector 27 about its point of rotation 37 until such disconnector 27 bears against the trigger sear 11, as shown. In this position the cam portion 32 of the disconnector 27 is in its uppermost position.

FIG. 4 illustrates the cocking or tensioning operation occurring between the breechblock mechanism and the trigger mechanism. During such time as there is undertaken the previously explained lateral movement of the cocking or tensioning lever 14 the breechblock cylinder 3 is moved rearwards. The firing pin member 9 in its previously considered forward "squeezed-off" or non-loaded position, as shown in FIG. 4, likewise moves rearwardly together with the breechblock cylinder 3 and thus releases the trigger sear 11. Spring member 16 lifts this trigger sear 11 until it contacts its non-illustrated stop, and the trigger sear assuming the position of FIG. 4 which conveniently can be designated as the catch position for the firing pin member 9. During the rearward movement of the breechblock cylinder 3 the pivot bolt member 4 also moves rearwards. Consequently, this pivot bolt 4 during such rearward travel moves onto the cam portion or piece 32 of the disconnector 27, forces such downwardly to rotate about its point of rotation 37 and at the same time overcomes the force of the spring member 28 tending to urge or load the disconnector 27 in the clockwise direction. In this position of the disconnector 27 it releases the trigger arm or rod 26 which, in turn, owing to the action of the spring member 25 is brought into a position where the screw member 18 contacts the handle or stock portion 15.

FIG. 5 illustrates the breechblock mechanism in its closed position and the trigger mechanism in its set condition. During closing movement of the cocking or tensioning lever 14, the breechblock cylinder 3 is moved forwards. The firing pin member 9 simultaneously moves forwards together with the breechblock cylinder 3 until the nose member 35 of this firing pin 9 is held by the catch nose 29 of the trigger sear 11, urged by the spring member 16 upwards until it makes contact with the firing pin-nose member 35. The breechblock cylinder 3 continues to move for a certain distance until it contacts the barrel 1; this pre-cocking path is conveniently designated the firing path.

The pivot bolt 4 mounted in the breechblock cylinder 3, likewise displaces forwards, slides over the cam piece 32 of the disconnector piece 27 and releases the latter. Now spring member 28 presses the disconnector 27 forwards until its nose member 33 bears against the nose member 34 of the trigger rod or arm 26. In this position the trigger mechanism is set that is to say, is in a preparatory state for firing or propelling a cartridge.

When firing a cartridge while employing a pressure point squeeze or triggering, the trigger tongue or trigger member 17 is pressed rearwardly. Consequently, the spring member 25 between the screw 24 and the countersupport 31 is tensioned. During this movement, conveniently termed the initial trigger squeeze, there is overcome the path through which the pressure point screw 20 must move until its contacts the countersupport 31, this displacement path being adjustable by means of the screw member 18. The

somewhat stronger spring 22, arranged at the pressure point screw 20 between the trigger arm 26 and the pressure point adjustment nut 23, therefore forms upon contact with the countersupport 31 a resistance (pressure point) which can be felt. Depending upon the pre-bias of this spring 22 by means of the nut 23, it is possible to regulate the pressure point so as to be less pronounced or stronger, as desired. If pressure is applied to the trigger arm 26 via this impact arrangement, in that the spring 22 is still further compressed, then, the trigger arm-nose member 34 moves further downwards and releases the disconnector 27. The disconnector 27, urged forwardly by the spring 28, impacts against the rearmost region 11a of the trigger sear 11 through the action of its cam portion or lifting nose 32a, thereby causing the trigger sear 11 to rotate in counterclockwise direction about the point of rotation 30 and overcoming the force of the spring 16. As a result, the catch nose 29 is pressed downwardly and therefore releases the firing pin member 9. Firing pin member 9 is displaced forwardly owing to the action of the tensioned firing pin spring 10 and thereby fires the cartridge.

When firing the cartridge with a double-hair trigger the interengagement of the nose members 34 and 33 of the trigger arm 26 and the disconnector 27 are adjusted by means of the screw member 18 to be so fine that the smallest displacement path of the trigger 17 in the direction of trigger movement releases the disconnector 27. The pressure point screw 20 must be turned back; its impact portion 36 should not contact the countersupport 31. Now, only the spring 25 of the double-hair trigger screw 24 acts upon the trigger arm 26 and therefore upon the trigger 17. Since it is also possible to adjust the spring 25 by means of the double-hair trigger screw 24 there is possible an optional adjustment of the weight of the double-hair trigger.

The trigger mechanism consisting of three main components (trigger seat 11, disconnector 27, trigger arm 26) can be adjusted both for double-hair triggers as well as also for pressure-point triggers. The function is extremely simple. The trigger mechanism possesses a short release time and a light-action of the impact of the disconnector 27 upon the trigger sear 11 which, in turn, releases the firing pin 9, and does not affect the firing precision.

The herein described and illustrated angle-lever breechblock mechanism together with the trigger mechanism is extremely simple both in operation and manufacture and in the area of high precision pistols provides a completely new and improved construction. By means of the cocking or tensioning lever it is possible to both actuate the striker or impact mechanism and the function of the breechblock mechanism as well as also to preset the trigger system. The trigger system is constructed in an extremely simple manner and can be adjusted, as mentioned above, both for pressure-point triggers as well as for double-hair triggers. The barrel dimensions and the bore relationships and also the sighting can be accommodated to the exceptional firing accuracy.

While there is shown and described present preferred embodiments of the invention, it is to be distinctly understood that the invention is not limited thereto but may be otherwise variously embodied and

practiced within the scope of the following claims. Accordingly,

What is claimed is:

1. A firearm comprising an angle-lever breechblock mechanism, and an actuating lever laterally mounted for actuating said angle-lever breechblock mechanism, said angle-lever breechblock mechanism comprising a breechblock cylinder and a breech lock, a connecting lever, a first pivot bolt for connecting one end of said connecting lever with said breech block cylinder, and a second pivot bolt for connecting the other end of said connecting lever with said breech lock; a trigger mechanism incorporating a trigger member operatively connected with a trigger arm and a displaceably mounted disconnector member cooperating with said trigger arm, said first pivot bolt being mounted at said breechblock cylinder and cooperating with said disconnector member such that upon opening said angle-lever breechblock mechanism and first pivot bolt acts upon said disconnector member to initially cause release of said trigger arm, whereupon said trigger arm and disconnector member interengage with one another to preset said trigger member.
2. A firearm as defined in claim 1, wherein said actuating lever is rigidly connected with said breech lock.
3. A target pistol comprising a trigger mechanism and a breechblock mechanism, said breechblock mechanism incorporating a breechblock cylinder and a breech lock, lever means for operatively interconnecting said breechblock cylinder with said breech lock, said breech lock being pivotably disposed adjacent said breechblock cylinder, said lever means having end portions respectively pivotably secured to said breechblock cylinder and said breech lock, and means carried by said lever means for setting said trigger mechanism.
4. The target pistol as defined in claim 3 wherein said breechblock mechanism in its cocked condition is supported and locked linearly by means of the interaction of said breech lock with said breechblock cylinder.
5. The target pistol as defined in claim 4, further including an outwardly pivotably mounted angle lever for actuating the breechblock mechanism.
6. A target pistol comprising a breechblock mechanism incorporating a breechblock cylinder and a breech lock, lever means for operatively interconnecting said breechblock cylinder with said breech lock, said breech lock being pivotably disposed adjacent said breechblock cylinder, said lever means having end portions respectively pivotably secured to said breechblock cylinder and said breech lock, a trigger mechanism incorporating a trigger member operatively connected with a trigger arm and a displaceably mounted disconnector member cooperating with said trigger arm, a pivot bolt being mounted at said breechblock cylinder and cooperating with said disconnector member such that upon opening breechlock mechanism said pivot bolt acts upon said disconnector member to initially cause release of said trigger arm, whereupon said trigger arm and disconnector member interengage with one another to set said trigger member.
7. A target pistol comprising a breechblock mechanism incorporating a breechblock cylinder and a breech lock, lever means for operatively interconnect-

ing said breechblock cylinder with said breech lock, said breech lock being pivotably disposed adjacent said breechblock cylinder, said lever means having end portions respectively pivotably secured to said breechblock cylinder and said breech lock, said breech lock includes a rearward portion pivotably secured to said pistol, an intermediate portion pivotably joined to said connecting lever end, and a forward portion of a

shape conforming to the rearward portion of said breechblock cylinder for longitudinal abutment therewith.

5 8. The target pistol as defined in claim 7 wherein said breech lock pivot axis is in intersecting alignment with the longitudinal axis of said breechblock cylinder.
